7 Claims. (Cl. 250—20)

This invention relates to a radio device, and more particularly to a device for mixing signals with generated oscillations to produce a beat frequency signal.

5 An object of the present invention is to provide a device that is comparatively simple in structure and easily attachable to a conventional or ordinary type of longer wave or broadcast receiver to adapt said receiver for the reception of shorter

10 wave signals.

Another object of the present invention is to provide a short wave adapter for an ordinary or conventional broadcast receiver that is inexpensive to build as well as easy to install.

15 Another object of this invention is to provide a short wave adapter for an ordinary or conventional broadcast receiver that does not necessitate material changes in the circuit or structure of the broadcast receiver in order to be installed there-

20 with.

Another object of this invention is to provide a circuit for mixing signals with oscillations generated within said circuit that is efficient and stable in operation as well as void of unnecessary

25 complexities.

Another object of the present invention is to provide a circuit for a radio device having an oscillating thermionic tube therein, that permits control of the frequency of the oscillations and

30 that generates harmonic oscillations and utilizes these harmonic oscillations in the reception of signals in different frequency bands.

Another object of the present invention is to provide a circuit for a device to be used in conjunction with an ordinary or conventional radio receiver in the reception of short wave signals that permits the reception of either short wave or broadcast signals without change of physical connections between the device and the receiver.

35 Another object of the present invention is to provide a circuit for a device to be used in conjunction with an ordinary or conventional radio receiver in the reception of short wave signals that lends itself to neatness and compactness

40 of design into a unitary structure.

Another object of the present invention is to provide a circuit for a device for mixing signals with oscillations generated therein, that eliminates the necessity of voltages of detrimental magnitude between the inductances utilized in

45 the circuit, and between the turns of the individual inductances.

Another object of the present invention is to provide a circuit for a device for mixing signals

a common low potential connection between the inductances utilized.

Another object of this invention is to provide a device that utilizes the shield element therefor as a base, and housing for the parts thereof.

5 Another object of the present invention is to provide an improved method of receiving signals in different short wave bands.

Another object of the present invention is to provide a method of receiving a warning or notice of the transmission of a local short wave station while listening to a broadcast program.

Other objects and advantages of this invention will be apparent from the accompanying specification and drawings wherein a preferred 15 form of the present invention is clearly illustrated and described.

In the drawings:

Fig. 1 is a wiring diagram showing a circuit of a preferred form of the present invention, with 20 portions of the circuit of a broadcast receiver shown to indicate a method of connecting thereto.

Fig. 2 is a wiring diagram showing a modification of the present invention.

Fig. 3 is a side elevation showing a preferred 25 form of construction of the present invention.

Fig. 4 is a bottom view with the cover removed showing the arrangement and mounting of the parts in a unit such as that shown in Fig. 3.

Fig. 5 is a perspective view of a preferred 30 form of inductance unit for use in the present device.

Fig. 6 is a detail view of the subassembly employed in a unit such as that shown in Fig. 4, with some parts shown in section and some in 35 elevation.

With particular reference to Fig. 1, an antenna 1 is connected to one end of an inductance or tuning coil 10 thru a lead 2, and to one end of an inductance or primary coil 12. The other end of the inductance or tuning coil 10 is coupled or connected to a grid or control electrode 14 of a thermionic tube 16 thru a condenser 18. A resistor 20 is connected across the condenser 18, and the condenser 18 and resistor 20 form a grid condenser 40 and grid leak. A variable condenser 22 is connected across the inductance 10 forming a tunable resonant circuit 4 for accomplishing the tuning. The other end of the inductance or primary coil 12 is connected to a suitable lead 24 which is adapted to be connected to an antenna binding post or terminal 11 of a conventional radio broadcast receiver.

50 The term broadcast receiver is understood to refer to any standard type of receiver capable of receiving longer wave signals 55.

than are to be received thru the use of the present invention in combination therewith. Since that receiver is not a part of the present invention, but may be of most any type or make well known to those skilled in the art, only the parts of the circuit have been shown that indicate an example of the connections thereto. In the exemplary portion of the input circuit of a broadcast receiver that is shown, the antenna binding post or terminal 11 is connected to one end of a primary coil 13 of an antenna coupling unit 17. The other end of the primary coil 13 is connected to ground at 15. The primary coil 13 is magnetically coupled with a secondary coil 19 of the coupling unit 17, and that secondary coil 19 has a variable condenser 21 connected thereacross to form a tunable resonant circuit 23 for tuning the broadcast receiver to a predetermined or desired frequency. One end of the secondary coil 19 is connected to an input or control electrode 25 of a thermionic amplifier tube 27. The thermionic amplifier tube 27 has beside the input or control electrode, an anode element 29, an auxiliary grid element 31, a cathode element 33, and a heater element 35 therein, and all of said elements as well as the other end of the secondary coil 19 are provided with suitable leads for connection to the remainder of the circuit of the broadcast receiver.

30 An inductance or feed-back coil 26 is magnetically coupled with the primary coil or inductance 12, and has one of its ends connected to a cathode or electron emitting element 28 of the thermionic tube 16. The other end of the inductance or feed-back coil 26 is connected to the antenna 1 and to a shield element 30. There is also magnetic coupling between the inductances 12 and 26 and the inductance 10. However, the inductances 12 and 26 are in closer magnetic relation than the inductances 26 and 10 or the inductances 12 and 10.

An anode or plate electrode 32 of the thermionic tube 16 is connected to an auxiliary or screen grid 34 of that tube thru a resistor 36, and to a suitable lead 38 which lead is adapted to be connected to a suitable source of potential on a standard broadcast receiver. That source of potential is preferably the potential obtained from an anode or screen grid of one of the tubes in the broadcast receiver, or directly from the anode potential supply circuit of the broadcast receiver. As shown as an example, the lead 38 is connected to an auxiliary or screen grid 39 of a thermionic amplifier tube 41 of the broadcast receiver. This is one preferred source because the potential thus obtained is practically constant, and is easily accessible by making connection to a tube prong. The tube shown is an audio frequency amplifier tube in the broadcast receiver, and hence has an anode 43 connected thru a primary winding 45 of an output transformer 47 to a lead 49 thru which the potential is provided from the receiver power source. The auxiliary or screen grid 39 is connected to the lead 49 thru a resistor 51. A secondary winding 53 of the output transformer 47 is connected to a voice coil 55 of a loud speaker or reproducing device 57. The thermionic amplifier tube 41 has therein, beside the auxiliary or screen grid 39 and the anode 43, an auxiliary grid 59, a control grid 61 and a filament 63. The auxiliary grid 59 is connected to the mid point of the filament 63, while the control grid 61 and filament 63 are provided with suitable leads for connection to the remainder of the

circuit of the broadcast receiver. The condensers 65 and 67 connected to the anode 43 and screen grid 39 respectively, and to ground at 69 and 71 respectively are by-pass condensers. A heater element 40 of the thermionic tube 16 is connected to suitable leads 42 and 44, which leads are adapted to be connected to a suitable source of potential on the broadcast receiver which is preferably the source of heater potential for the tubes of the broadcast receiver that are designed for the same heater voltage. As shown, they are connected to the heater element 35 of the thermionic tube 27. This is convenient, because the connections of the leads 42 and 44 may be made to the heater prongs of the tube 27.

With particular reference to Fig. 2, an inductance or primary coil 50 has one end connected to the antenna 1 and its other end connected to a suitable lead 24 adapted to be connected to the antenna post or terminal of a conventional broadcast receiver. An inductance or tuning coil 52 has one end connected to a grid or control electrode 54 of a thermionic tube 56 thru a condenser 58, and its other end connected to 25 the shield element 30 and to ground at 62 thru a suitable lead 60. A variable or tuning condenser 22 is connected across the inductance 52 to form a tunable resonant circuit 6 and accomplish the tuning of that inductance. A resistor 64 is connected to the grid or control electrode 54 and to the lead 60. An inductance or feed-back coil 66 is magnetically coupled with the inductance or primary coil 50. The inductance 66 and an inductance 50 are coupled with 35 the inductance 52. However, the coupling between the inductances 66 and 50 is closer than that between the inductances 66 and 52 and the inductances 50 and 52. One end of the inductance 66 is connected to the shield 30 and 40 lead 60, and the other end of the inductance 66 is connected to a cathode or electron emitting element 68 of the thermionic tube 56. An anode or plate electrode 70 of the thermionic tube 56 is connected to a suitable lead 38 that is adapted 45 to be connected to a source of potential in a manner similar to that previously explained for the lead 38 of Fig. 1. A heater element 72 of the thermionic tube 56 is provided with suitable leads 42 and 44 similar to those of Fig. 1. 50

With particular reference to Figs. 3 and 4, the structure shown is a form preferable for the embodiment of the circuit of Fig. 1, and reference numerals similar to those used in Fig. 1 refer to corresponding parts. The shield 30 is 55 made in the form of a cup that serves as a base for the unit as well as a housing and mounting for the parts thereof. A socket 80 is secured to the end of the cup-shaped shield 30 by means of rivets such as 82. The socket 80, adapted to 60 receive the tube 16, is for supporting the tube. The socket 80 is provided with terminals such as 84, 86, 88 and 90 for making connections to the elements of the thermionic tube 16, and a lead 92 provided with a clip 94 and extending thru 65 a grommet or eyelet 96 in the end of the cup-shaped shield 30 is provided for making connection to the grid or control electrode terminal 98 of the thermionic tube 16. A grommet 100 preferably made of insulating material is mounted in 70 a suitable aperture in the side of the cup-shaped shield for the protection of the leads 2, 38, 24, 44 and 42 that extend therethrough. The lead 2 connects to the shield 30. The leads 42 and 44 connect to the heater connection terminals such 75

as 90 on the socket 80, and are preferably twisted so as to neutralize or prevent the radiation of an alternating field therefrom. The lead 24 connects to a terminal 102 on a coil form 104 to provide for the connection between one end of the primary coil for inductance 12 and the antenna post or terminal on the broadcast receiver. The lead 38 connects to the anode or plate connecting terminal 88 on the socket 80, and the resistor 36 is connected between that anode or plate terminal 88 and the auxiliary or screen grid terminal 36. The cathode or electron emitting element connector terminal 84 is connected thru a lead 106 to a terminal 108 on the coil form 104.

A strip of insulating material 110 forms a support for the parts other than those mounted directly on the shield 30 or socket 80, and that strip of insulating material or support 110 is positioned within the cup-shaped shield 30 between ribs 111 at its ends. The ribs 111 may be formed in the shield or held in place by any suitable means such as soldering. A rivet or other suitable fastening means 112 secures a lug 114, a strip of insulating material 118 and a resilient condenser plate 120 to the strip of insulating material or support 110 near one end of that strip or support. The rivet or fastening means 112 also makes an electrical connection between the lug 114 and the resilient plate 120. Then, the lug 114 is soldered to the shield element 30 so that it aids in holding the strip of insulating material or support 110 in position, and at the same time connects the resilient plate 120 to the shield element 30. A lead 122 makes a connection between the common terminal of the inductances 12, 26 and 10 and the shield element 30. A stationary condenser plate 116 is preferably secured to the strip of insulating material 110 intermediate the strip of insulating material 118 and the strip of insulating material or support 110, and is spaced or insulated from the rivet 112. Then, a screw or other suitable connecting or fastening means 124 provided with a nut 126 and a washer 128 secures the stationary condenser plate 116 to the strip of insulating material 110 near its other end, and makes electrical connection therewith. The screw 124 also makes electrical connection with a lug or connector 130 of a condenser 18 so as to provide a connection between the stationary plate 116 and one side of the condenser 18, and to secure the condenser 18 in position on the insulating support 110. The resistor 20 is connected across the condenser 18 and supported by its connection to the lug 130 and a lug 132 of the condenser 18. A lead 134 connected at one end to a terminal 136 and at its other end to the screw 124 forms a connection between one end the inductance or coil 20 and the condenser 18 and the stationary plate 116. A collar 138 is secured to the shield element 30 and has a screw 140 threaded therein. The screw 140 has one end urging against the resilient plate 120, and extends thru the collar 138 and shield 30 so that its other end is outside the shield element 30. The end of the screw 140 that is outside the shield element 30 is provided with an insulating knob 142 and a lock nut 144 that aids in locking the knob 142 in position on the screw 140, so that by manually turning the knob 142, the screw 140 serves to adjust the position of the resilient plate 120, and hence to tune the circuit.

With particular reference to Fig. 5, terminals 102, 108, 136 and 146 are preferably secured to the coil form 104, and in the present preferred modi-

fication those terminals are in the form of pins secured to the form 104 by driving those pins into the form. All of the inductances or coils necessary for the operation of the present device are wound in suitable grooves or recesses 150 and 152 cut or formed in the surface of the form 104. The leads from, or ends of, the respective inductances or coils are then connected to their particular pins or terminals. The pin or terminal 146 forms a common terminal for one end or lead from each of the inductances, while the pin or terminal 102 provides a terminal for the other end of the primary coil or inductance 12, the pin or terminal 108 forms the terminal for the other end of the feed-back coil 26, and the pin or terminal 136 forms a terminal for the other end of the tuning coil or inductance 10. An aperture 148 is provided in one end of the form 104 for the accommodation of a mounting screw.

With particular reference to Fig. 6, reference numerals previously used and explained refer to similar parts. However, in this view it may be seen that the feed-back coil or inductance 26 is wound in the bottom of the groove or recess 152 and the primary coil or inductance 12 is wound over the feed-back coil or inductance 26 in the same groove or recess. The tuning coil or inductance 10 is wound in a groove or recess 150. It has been found that all of these coils or inductances may be jumble-wound. The coils are all wound in the same direction. The form 104 is secured to the strip of insulating material or support 110 by means of a screw 154, and an aperture 156 is provided through the stationary plate 116 and the strip of insulating material 118 to permit passage of the head of the screw 154 therethrough. Hence, it may be seen that a sub-assembly formed with the part that is shown in Fig. 6 may be assembled and some of the connections made between the parts before the sub-assembly is placed within the shield element 30, thus leading to ease in manufacture and assembly.

In the operation of the unit, signals are picked up by the antenna 1 and carried by the lead 2 to primary coil or inductance 12, and thence through the lead 24 to the antenna terminal of an ordinary or conventional broadcast receiver. The potentials for the heater 40 and anode or plate electrode 32 of the thermionic tube 16 are preferably provided through the leads 42 and 44 for the heater, and 38 for the anode or plate electrode 32 respectively, from the broadcast receiver. The potential for the screen or auxiliary grid 34 is also provided from the lead 38 through the resistor 36. The potential drop across the resistor 36 causes the potential of the screen or auxiliary grid 34 to be somewhat lower than that of the anode or plate electrode 32. The heat of the element 40 conducted to the cathode or electron emitting element 28 causes the cathode or electron emitting element to discharge a stream of electrons to the anode or plate electrode 32, which stream or flow of electrons is controlled by the action or potential of the grid or control electrode 14. The grid or control electrode 14 is coupled to the resonant circuit 4, formed by the tuning coil or inductance 10 and the variable condenser 22, thru the condenser 18 and resistor 20.

The tuning or varying of the resonant frequency of the resonant circuit 4 is accomplished by tuning, or varying the capacity of the variable condenser 22. The resonant frequency to which the resonant circuit 4 is tuned controls the action of the grid or control electrode 14, and the oscil-

lating frequency of the circuit. Regeneration, which effects oscillatory action or oscillation of the circuit, is accomplished thru the action of the feed-back coil or inductance 26 that is connected in series with the cathode or electron emitting element 28 and magnetically coupled with the inductances 10 and 12. It is particularly the coupling between the inductances 26 and 10 that provides the regeneration to effect the oscillatory action of the circuit. In considering the operation, it may be understood that the grid controls the cathode current as well as the plate current since the stream of electrons flowing from the cathode to the plate is what is actually controlled, and a change in this flow effected by the grid or control electrode affects both the plate and cathode currents. Consequently, by reactively or electromagnetically coupling the cathode and grid circuits through the coupling between the inductances 26 and 10, and properly regulating or establishing that coupling and the inductance values, the circuit including the tube 16 acts as an oscillation generator, the frequency of the oscillations of which are controlled by the values of the inductance 10 and condenser 22. By accomplishing this regeneration or regenerative action with the inductance 26 in the cathode circuit instead of in the usual manner of having an inductance in the anode or plate circuit, the potential difference between the turns of the feed-back coil or inductance is kept low, and it is possible to have the common low potential connection for the inductances of the unit which prevents any potential difference of detrimental magnitude between the various inductances, and aids regeneration. The common connection between inductances also permits the connection of a common point in each of the inductances to the shield element which reduces stray capacities between the units and variations resulting therefrom, as well as reducing or eliminating the effect of body-capacity in tuning.

Since the inductances 12 and 26 are mounted in the same groove or recess in the form as best shown on Fig. 6, the coupling between those inductances is closer than the coupling between the inductances 10 and 12 and the inductances 10 and 26. However, due to the comparatively short distance between the inductances 10 and 12 and the inductances 10 and 26, there is coupling between those inductances. Due to this coupling between the inductances, the oscillating energy generated in the thermionic tube 16 is mixed with the signals or signal energy picked up by the antenna 1 and transmitted to the inductance coil. This mixture of signal and oscillating energy produces beat frequency signals, the frequencies of which are equal to the difference of the signal frequency and oscillator frequency.

Hence, if the tuning elements of the broadcast receiver are set to a fixed position, so that it excludes signals of a frequency other than that to which it is tuned, the beat frequency signals of a frequency to which the broadcast receiver is tuned are amplified and reproduced by the broadcast receiver. Since variation of the capacity of the condenser 22 varies the resonant frequency of the resonant circuit 4, and consequently the oscillator frequency, various signals may be selected by tuning the condenser 22 so that the beat frequency produced with the selected signal is equal to the frequency to which the broadcast receiver is tuned. Since broadcast signals within the frequency range of the broadcast receiver itself are picked up by the antenna 1 at the same time the

other signals are picked up, it is necessary, in order to prevent their reception and reproduction by the broadcast receiver, to tune that receiver to a frequency at which no broadcast signals are received. At times when it is desired to receive a broadcast program, and yet have a notice or warning when a short wave station that transmits signals intermittently is transmitting, the broadcast receiver may be set so that it receives the desired program, and then the condenser 22 may be set so that the oscillator frequency will be such that when the short wave station is transmitting, a heterodyne signal in the form of a whistle will be received. The short wave station may then be received by tuning the broadcast receiver away from the broadcast program and to a point at which the short wave station is clearly received.

Since the oscillator also generates harmonic frequencies that are multiples of its fundamental frequencies, it is possible by properly choosing the oscillator frequency and the frequency to which the broadcast receiver is tuned, to receive signals in different short wave frequency bands without materially changing the oscillator circuit. That is, for example, if the broadcast receiver is set to receive a signal frequency of 600 kilocycles, and the oscillator is designed so that its frequency which is governed by the constants of the resonant circuit 4, may be varied from 1600 kilocycles to 2300 kilocycles, a signal having a frequency of 2400 kilocycles may be received by tuning the resonant circuit 4 so that the fundamental frequency of the oscillator is 1800 kilocycles. Then, the signal in a different frequency band, such as one having a frequency of 400 kilocycles may be received by adjusting the resonant frequency of the resonant circuit 4 so that its fundamental frequency is 1700 kilocycles and its second harmonic frequency is consequently 3400 kilocycles. It may be noted that in the first instance the difference between the signal frequency and the oscillator frequency was equal to the frequency to which the broadcast receiver was tuned, and in the second instance the difference between the signal frequency and the oscillator second harmonic frequency was equal to the frequency to which the broadcast receiver was tuned.

The modified circuit shown in Fig. 2 operates in substantially the same manner as the circuit shown in Fig. 1, and the regeneration or oscillatory action is accomplished in substantially the same manner. However, in this circuit the different type of tubes has been shown and the resistor or grid leak 64 is connected across the condenser 58 thru the inductance 52. In this circuit also, the primary coil or inductance 50 is magnetically coupled with the inductances 66 and 52, but does not have the terminal or end connected to the common terminal of the inductances 52 and 60.

Either the circuit shown in Fig. 1 or that shown in Fig. 2 could very well be made into a unit as shown in Figs. 3 and 4, although the particular structure of Fig. 4 shows a unit embodying the circuit of Fig. 1. In this type of unit, the inductances may be jumble wound on a form such as that shown in Fig. 5, and in a way more fully disclosed in Fig. 6. Then, the condenser may preferably be formed as shown in Fig. 6 with a stationary plate 116 cemented or otherwise secured to a strip or sheet of insulating material 118. The other plate of the condenser 120 is made of resilient material that is normally biased so as to flex away from the plate 116. The capacity of the condenser is then a minimum when the plate

120 is fully flexed away from the plate 116. To facilitate ease of assembly, the inductance unit shown in Fig. 5 is secured to the strip of insulating material or the mounting 110. The resistor 20 and condenser 16, as well as the variable condenser formed by plates 116 and 120 are also secured to the mounting 110 and the connections made between the parts of the subassembly thus formed before the subassembly is placed in the 10 base formed by the shield element 30. The socket 80 and resistor 36 are secured to the base or shield element 30 and the leads 2, 42, 44 and 38 connected to their respective terminals before the subassembly is put in place. The strip of insulating material or mounting 110 is positioned by 15 means of ribs 111. The screw 140 is threaded into the collar 138 that is secured to the shield element 30, and serves as a means of adjusting the distance between the plates 116 and 120 to 20 vary the capacity of the condenser formed thereby. The insulating knob 142 is provided on the screw 140 outside of the shield element 30 to facilitate manual adjustment of the capacity of the variable condenser to accomplish the tuning 25 of the unit as described for Fig. 1.

The leads 2, 24, 38, 42 and 44 are provided for making connections with the broadcast receiver as shown in Fig. 1. After thus being connected, the operation is substantially as previously described.

Although the invention illustrated and described represents a preferred form or embodiment, others may be used, all coming within the scope and spirit of the claims which follows.

35 What is claimed is:

1. A short wave adapter for a broadcast receiver having an antenna therefor and an antenna terminal thereon comprising in combination, a thermionic tube having an anode, a control electrode, an auxiliary grid, a cathode, and a heater element therein; a resistor connected between said anode and said auxiliary grid; a lead connected to the anode for applying a potential to said anode; a shield element; a grid condenser and grid leak; a tuning inductance having one end connected to said control electrode thru said grid condenser and grid leak and its other end connected to said shield; a variable condenser connected across the tuning inductance and forming a tunable resonant circuit therewith; a feed-back coil having one end connected to said cathode and its other end connected to the shield; a primary inductance having one end connected to the shield and adapted to be connected to said antenna and its other having a lead thereon adapted to be connected to said antenna terminal; and means for applying a heating potential to said heater element; said inductances being magnetically coupled, with the coupling between said primary inductance and said feed-back inductance closer than the coupling between the tuning and feed-back inductances.

2. A short wave adapter for a broadcast receiver having an antenna therefor and an antenna terminal thereon, comprising in combination, a thermionic tube having an anode, a control electrode, a cathode, and a heater element therein; a lead connected to said anode for applying a potential to said anode; a shield element; a grid condenser, a tuning inductance having one end connected to said control electrode thru said grid condenser and its other end connected to said shield; a variable condenser connected across

the tuning inductance and forming a tunable resonant circuit therewith; a resistor connected across said tuning inductance and grid condenser; a feed-back coil having one end connected to said cathode and its other end connected to the shield; a primary inductance having one end with a lead thereon for making connection to said antenna and its other end having a lead thereon for making connection to said antenna terminal; and means for applying a heating potential to said heater element; said inductances being magnetically coupled, with the coupling between said primary inductance and feed-back inductance closer than the coupling between the tuning and feed-back inductances.

3. A short wave adapter for a broadcast receiver having an antenna therefor and an antenna terminal thereon, comprising in combination, a thermionic tube having an anode, a control electrode, and an electron emitting element therein; means for applying a potential to said anode; means for heating said electron emitting element; a condenser; a resistor forming a leak for said condenser; a first inductance having one end connected to said control electrode thru said condenser; a second inductance having an end connected to said electron emitting element and its other end connected to an end of said first inductance; a primary inductance coupled to said inductances and having leads connected to its ends for making connection with said antenna and said antenna terminal; and a variable condenser connected across said first inductance and forming a tunable resonant circuit therewith.

4. A short wave adapter for a broadcast receiver having an antenna therefor and an antenna terminal thereon comprising in combination, a thermionic tube having an anode, a control electrode, an auxiliary grid, a cathode, and a heater element therein; a resistor connected between said anode and said auxiliary grid; a lead connected to the anode for applying a potential to said anode; a shield element; a grid condenser and grid leak; a tuning inductance having one end connected to said control electrode thru said grid condenser and grid leak and its other end connected to said shield; a variable condenser connected across the tuning inductance and forming a tunable resonant circuit therewith; a feed-back coil magnetically coupled to the tuning inductance and having one end connected to said cathode and its other end connected to the shield; a primary inductance magnetically coupled to the tuning inductance and having one end connected to the shield and adapted to be connected to said antenna and its other having a lead thereon adapted to be connected to said antenna terminal; and means for applying a heating potential to said heater element.

5. A short wave adapter for a broadcast receiver having an antenna therefor and an antenna terminal thereon, comprising in combination, a thermionic tube having an anode, a control electrode, a cathode, and a heater element therein; a lead connected to said anode for applying a potential to said anode; a shield element; a grid condenser; a tuning inductance having one end connected to said control electrode thru said grid condenser and its other end connected to said shield; a variable condenser connected across the tuning inductance and forming a tunable resonant circuit therewith; a resistor connected across said tuning inductance and grid condenser; a feed-back coil magnetically coupled to the tuning inductance and having

one end connected to said cathode and its other end connected to the shield; a primary inductance magnetically coupled to the secondary inductance and having one end with a lead thereon for making connection to said antenna and its other end having a lead thereon for making connection to said antenna terminal; and means for applying a heating potential to said heater element.

6. In a unitary radio device, the combination comprising, a plurality of inductances wound on a form and including a primary inductance, a tuning inductance and a feed-back inductance, said inductances being provided with terminals secured to said form; a variable condenser connected across said tuning inductance to form a tunable resonant circuit; a thermionic tube having an anode, a control electrode, an auxiliary grid, a cathode, and a heater therein; a grid leak and grid condenser for coupling said tunable resonant circuit to said control electrode; a cup-shaped shield element; a socket secured to the end of said cup-shaped shield for holding said tube and making connections thereto; said variable condenser, inductances, and grid leak forming a subassembly and mounted within said shield; means extending to the outside of said shield for adjusting said variable condenser; said shield forming a base for said device; and leads extend-

ing outside said shield from the ends of said primary inductance, said heater, and said anode for making connections thereto.

7. In a unitary radio device, the combination comprising, a plurality of coupled inductances wound on a form and including a primary inductance, a tuning inductance and a feed-back inductance; said inductances having a common connection, which common connection is at a low D. C. potential; a variable condenser connected across said tuning inductance to form a tunable resonant circuit; a thermionic oscillator tube having an anode, a control electrode, and an electron emitting element therein; means coupling said control electrode to said tunable resonant circuit to control the frequency of oscillations of said thermionic tube; a cup-shaped shield element; a socket secured to the end of said cup-shaped shield for holding said tube and making connection to one of said electrodes and said element, 20 said shield forming a base for said device; said variable condenser and said inductances mounted within said cup-shaped shield; means extending to the outside of said shield for adjusting said variable condenser. 25
